CLAIM

The ornamental design for an electric milk frother, as shown and described.

DESCRIPTION

FIG. 1 is a perspective view of an electric milk frother showing the new design.

FIG. 2 is another perspective view of the electric milk frother of FIG. 1.

FIG. 3 is a magnified perspective view of the section in callout A of the electric milk frother of FIG. 2.

FIG. 4 is a front view of the electric milk frother of FIG. 1.

FIG. 5 is a rear view of the electric milk frother of FIG. 1.

FIG. 6 is a side view of the electric milk frother of FIG. 1.

FIG. 7 is an opposite side view of the electric milk frother of FIG. 1.

FIG. 8 is an enlarged top view of the electric milk frother of FIG. 1; and,

FIG. 9 is an enlarged bottom view of the electric milk frother of FIG. 1.

The dashed lines in the drawings represent environmental structure that forms no part of the claimed design.
